GEORGE C. BAILEY, OF PITTSBURG, PENNSYLVANIA.

Letters Patent No. 98,011, dated December 21, 1869.

IMPROVEMENT IN HYDRANTS.

To all whom it may concern:

Be it known that I, GEORGE C. BAILEY, of the city of Pittsburgh, in the county of Allegheny, and State of Pennsylvania, have invented a new and useful Improvement in Hydrants; and I do hereby declare the following to be a full, clear, and exact description thereof, reference being had to the accompanying drawing, making a part of this specification, which shows a vertical sectional view of my improved valve.

The nature of my invention consists in an improved construction of a hydrant or other like valve.

To enable others skilled in the art to make and use my invention, I will proceed to describe its construction and mode of operation.

The disk-valve *a*, of the usual or any known construction, is screwed on to or otherwise attached to the lower end of the discharge-pipe or plunger *b*.

Its lower face has packing *e*, which fits neatly on to the seat *c*.

Apertures *a'* are made in the valve *a*, through which, when the valve *a* is raised from its seat *c*, the water passes from the supply-pipe *d*, upward through the discharge-pipe *b*, and out at the spout above.

Surrounding the valve *a*, and valve-seat, *c*, which latter forms a part of it, is a valve-chamber, *f*, made slightly bell-mouthed, as at *f*, so as, when putting it in place, the more easily to be guided on to the upper end of the supply-pipe *d*, on to which it is screwed, a packing-ring or gasket, *e*, being interposed between the two.

The valve-chamber *f* extends up above the upper face of the valve *a*, a sufficient distance, so that a collar, or annular ring, *i*, bored to the exact size of the pipe *b*, may be slipped thereon above the valve *a*, and screwed into the upper end of the chamber *f*, leaving sufficient room for the play of the valve.

Through this collar *i*, a small waste-hole, *i'*, is made.

Between this collar *i* and the valve *a*, and resting on the upper face of the valve, is an annular packing-ring, *o*, of India rubber, or other suitable material, which moves only with the valve.

When the valve is raised, and communication is opened from the supply to the discharge-pipes, the packing-ring *o* comes against the lower end of the waste-passage *i'* and closes it.

When the valve is seated, and the outflow of water is stopped, the waste *i'* is uncovered, and the water in the discharge-pipe or plunger *b* escapes.

It is often necessary or desirable to remove the valve-chamber and valve for repairs, cleaning, &c.

To do this easily, I attach to the plunger-pipe *b*, a radially-projecting lug, *s*, and make a vertically-projecting lug *s'*, on the upper end of the chamber *f*, in such relative adjustment, that as the plunger *b* is turned or rotated, one lug will engage the other, and so the turning of the pipe *b* as a wrench, will screw the chamber *f* on or off the supply-pipe *d* at the joint *d'*, as may be desired; but for the purpose of removing or putting in place the valve-chamber, I do not limit myself to the use of the lugs *s s'*, since other equivalent device for locking or interlocking the two, such as a crab-clutch, key, or feather, may be substituted therefor.

The collar *i* may, if so desired, be cast with the valve-chamber as a part thereof, in which case the lower part of the valve-chamber, containing the valve-seat, may screw on and off, so as to admit of the insertion of the valve.

Nor is it necessary that the valve-seat be cast as a part of the valve-chamber, but only that it be separate and removable from the supply-pipe *d*.

The valve *a*, it will be observed, in a hydrant constructed as described, always shuts against the pressure of the water.

What I claim as my invention, and desire to secure by Letters Patent, is—

1. The lug *s*, attached to or forming part of the hollow plunger and discharge-pipe, in combination with the removable valve-chamber *f*, having a corresponding lug, *s'*, all arranged and combined substantially as set forth.

2. The discharge-pipe *b*, lugs *s s'*, valve-chamber *f*, and joint *d'*, when combined in the manner substantially as shown and described.

3. A hydrant-valve seat inserted in or forming part of a removable valve-chamber, and a vertically-moving plunger or discharge-pipe, in combination with a locking-device constructed and operated substantially as described.

4. The discharge-pipe *b*, valve *a*, movable annular packing-ring *o*, and waste-passage *i'*, when combined as shown.

In testimony whereof, I, the said GEORGE C. BAILEY, have hereunto set my hand.

Witnesses:

JOHN GLENN,
THOS. B. KERR.
